W. S. KELLNER
ADVERTISING NOVELTY
Filed July 27, 1922

Inventor

W. S. Kellner

By *St. Alvinson & Co.*
Attorneys

UNITED STATES PATENT OFFICE.

WILLIAM S. KELLNER, OF BALTIMORE, MARYLAND.

ADVERTISING NOVELTY.

Application filed July 27, 1922. Serial No. 577,925.

To all whom it may concern:

Be it known that I, WILLIAM S. KELLNER, a citizen of the United States, residing at Baltimore, in the county of Baltimore City and State of Maryland, have invented certain new and useful Improvements in Advertising Novelties; and I do declare the following to be a full, clear, and exact description of the invention, such as will enable others skilled in the art to which it appertains, to make and use the same.

My invention relates to advertising novelties, and more particularly to advertising cards, such as postcards, the object being to provide a two-ply card whose plies are secured to each other at their edges to form a container for an advertising sheet, one ply being provided with a representation of an object having a movable closure, the closure representing part of said ply being cut from the latter, except for a hinge line upon which said part may be swung outwardly to disclose the advertising sheet.

With the foregoing in view, the invention resides in the novel subject matter hereinafter described and claimed, the description being supplemented by the accompanying drawing.

Figure 1 is a perspective view showing the obverse side of the card.

Figure 2 is a view similar to Fig. 1 but showing the closure representing part of the device swung open to disclose the advertising sheet.

Figure 3 is a perspective view showing the reverse side of the card.

Figure 4 is a vertical section on line 4—4 of Fig. 1.

Figure 5 is a view similar to Fig. 4 on line 5—5 of Fig. 2.

Figure 6 is a horizontal section on line 6—6 of Fig. 1.

Figure 7 is an elevation of a card displaying a different representation from that shown in the preceding figures.

Figure 8 is a vertical section on line 8—8 of Fig. 7.

In the drawings above briefly described, the numerals 1 and 2 designate the obverse and reverse plies of the card, these plies being preferably formed from a single sheet of cardboard folded upon itself on the line

3, although two separate pieces could be used if desired. I make provision however for joining all edges of each ply to the other ply, so as to form a complete container for an advertising sheet 4 and when the construction here disclosed is employed, the edges of the plies or the edges of one ply only, are preferably gummed so that by merely moistening the gum, the edges may be secured to each other after placing the advertising sheet 4 in the container.

The obverse face of the card, that is the ply 1, is painted or printed, or otherwise provided with a representation 5 of any desired receptacle or object having a movable closure. In Fig. 1, the representation 5 simulates a trunk, while in Fig. 7 the lower end of a coat is shown. The closure 70 simulating part of the representation 5 (the trunk top in Figs. 1 and 2 and the coat pocket flap in Fig. 7) is cut from the ply 1 as indicated at 6 with the exception of a hinge line 7, upon which the closure-representing part 8 may be swung outwardly for gaining access to the advertising sheet 4. I prefer to use a gummed seal 9 for the closure-representing part 8, and in Fig. 1, this seal is shown of such a design as to represent a lock for the trunk top.

The invention is preferably embodied in the form of a postcard and the obverse face 2 is provided with appropriate areas for the address, and additional advertisements, etc. Near one end or at any other suitable location, the ply 2 is formed with a slit 10 to permit postal inspection of the contents, so that it is not necessary to apply first-class postage.

The invention is simple and inexpensive yet will form an attractive and efficient advertising medium, whether embodied in the forms herein disclosed or in any of a great number of other forms which may be devised.

I claim:

A rectangular, advertisement-containing and mailing envelope sealed throughout its perimeter and having one side upon which to write an address; a portion of the other side of said envelope being provided with a pictorial representation of an object having a hinged closure, the closure-simulating

area of the representation being cut on three edges from said other side only on line spaced inwardly from the envelope edges, the other edge of said area representing the hinge line of the closure and forming a hinge permitting direct outward swinging of said area by the recipient to give access to the advertisement, the latter being covered and obscured by said area during transit of the envelope. ¹⁰ In testimony whereof I have hereunto affixed my signature.

WILLIAM S. KELLNER.
